UNITED STATES PATENT OFFICE

159,310

DISPLAY STAND FOR FOOD WASTE DISPOSAL UNITS

Enos Ray Ames, Wichita, Kans.

Application September 27, 1948, Serial No. 148,784

Term of patent 3½ years

(Cl. D80—9)

To all whom it may concern:

Be it known that I, Enos Ray Ames, a citizen of the United States, residing at Wichita, in the county of Sedgwick and State of Kansas, have invented a new, original, and ornamental Design for a Display Stand for Food Waste Disposal Units, of which the following is a specification, reference being had to the accompanying drawing, forming a part thereof.

Fig. 1 is a front perspective view of a display stand for food waste disposal units, showing my new design; and

Fig. 2 is a rear perspective view thereof.

I claim:

The ornamental design for a display stand for food waste disposal units, as shown.

ENOS RAY AMES.
